G. E. DAVIS

VANITY CASE

Filed March 19, 1924

Fig. 1.

Fig. 2.

Inventor
George E. Davis
by Bair & Freeman, Atty's.

UNITED STATES PATENT OFFICE.

GEORGE E. DAVIS, OF DES MOINES, IOWA.

VANITY CASE.

Application filed March 19, 1924. Serial No. 700,412.

To all whom it may concern:

Be it known that I, GEORGE E. DAVIS, a citizen of the United States, and a resident of Des Moines, in the county of Polk and 5 State of Iowa, have invented a certain new and useful Vanity Case, of which the following is a specification.

The object of my invention is to provide a vanity case of simple construction, peculiarly adapted for containing loose powder and having parts so arranged that the loose powder may be taken out in small quantities 10 on a powder puff.

Still a further object is to provide such 15 a vanity case having means whereby the body of the loose powder will be held in place and will not readily be spilled or scattered when the vanity case is being used for taking out a small amount of powder.

20 With these and other objects in view, my invention consists in the construction, arrangement and combination of the various parts of my device, whereby the objects contemplated are attained, as hereinafter more 25 fully set forth, pointed out in my claims, and illustrated in the accompanying drawings, in which:

Figure 1 shows a top or plan view of a 30 vanity case embodying my invention with the case open; and

Figure 2 shows a vertical, sectional view taken on the line 2—2 of Figure 1 with the case closed.

My vanity case has an ordinary bottom 35 member indicated in the accompanying drawings by the reference character 10. A top or cover member 11 is hinged thereto, as at 12.

It is well known that vanity cases are used 40 in large numbers for containing powder in so-called compact form. In such cases, the powder is pressed into the shape of a small disc with a rounded upper surface and is so treated in the manufacture as to be formed 45 into a body that retains its shape.

Powder in a compact form is in some ways not so satisfactory for use as loose powder.

Loose powder, however, is not used in a 50 vanity case that is carried from place to place, because it is so easily spilled and scattered about and also because it is hard to take a small amount of the powder out of the case on a powder puff or the like without spilling or scattering the powder.

55 It is my purpose therefore to provide a novel structure in connection with a vanity

case, which will hold loose powder without danger of spilling or scattering such powder, when the case is carried in the ordinary way, and which can still be easily operated for 60 taking up a small amount of powder on the powder puff without disturbing the main body of the powder or spilling or distributing the powder in an undesirable way.

I have therefore provided in the upper 65 part of the bottom 10 an annular plate 13 having a large central opening 14. The ring plate is hinged at one side, as at 15, of the side wall of the bottom member 10. At the opposite side of the bottom member 10, the 70 side wall thereof is provided with vertically spaced small inward projections 16.

The plate 13 may be sprung between the 75 projections 16 and then will be snugly held in place.

The plate 13 is inclined from its outer edge 80 inwardly and downwardly, as shown in Figure 2, and has at its inner end a flange or portion 17 extending downwardly at a slightly sharper angle to the horizontal.

A suitable disc 18 is placed just below the 85 opening 14 in the center of the plate 13. The disc 18 is of substantially greater diameter than the opening 14 in the plate 13, but of substantially less diameter than the bottom member 10.

It will be understood that while I have 90 illustrated a vanity case in the form of a round box and therefore have given to the plate 13 an annular form, the shape of the box may be varied and the shape of the circumference of the plate 13 would then be varied to correspond.

The disc 18 is suitably connected with the 95 plate 13 at one side thereof near the inner edge of said plate in such manner as to permit the disc 18 to be tilted downwardly from such connecting point or points. As an illustrative means for such connection, I have shown in the drawings two pins 19, 19, 100 extended through the disc 18 and plate 13 as shown and suitably headed.

A spring 20 is connected with the under- 105 side of the disc 18 and coacts with the bottom of the bottom receptacle 10, as shown for instance in Figure 2, for yieldingly holding the disc 18 at its upper limit of movement in contact with the flange 17.

The spring 20 may be a wire spring or 110 may have such shape as is suitable for the purpose.

In the practical use of my improved van-

- ity case, the plate 13 is sprung past the upper projections 16 and swung upwardly on its hinge 15, until access to the lower part of the bottom receptacle 10 may be had.
- 5 The disc 18 will drop away from the plate 13, except at its points of connection therewith, but on account of the fact that the disc projects beyond the pins 19, it will not swing downwardly so as to be in the 10 way when the plate 13 is raised to substantially vertical position.

Loose powder is then placed in the lower part of the bottom receptacle 10 of the vanity case to a height approximately level with 15 the lower surface of the disc 18 when the parts are in the position shown in Figure 2.

The plate 13 is then swung back toward its closed position with its edge sprung between the projections 16, as shown in Figure 20 2.

The spring 20 will readily push its way downwardly through the powder to contact with the bottom portion of the member 10.

The plate 13 may be stamped or otherwise 25 cut from a sheet of metal and pressed to shape. The inner edge of the plate 13 is cut in the ordinary way. A sharp edge 21 will be left to contact with the disc 18. This sharp edge will readily cut through any 30 powder that may rest on the disc 18.

Usually a powder puff 22 is carried in the vanity case above the plate 13. When it is desired to use powder from the box, the user 35 takes the powder puff and presses downwardly on the center thereof, swinging the disc 18 downwardly on the pins 19 with a pivotal movement. It is understood that enough play is permitted in the parts to allow of such movement.

40 It is obvious that when the disc 18 is pressed downwardly, there will be a slight draft of air outwardly under and around the edge of the flange 17, which will permit or cause enough loose powder for the purpose to move toward the upper central surface of the disc 18 from beneath the plate 13.

I find that mere vibration of the disc 18 causes the powder to move from beneath the ring plate toward the central portion of the 50 disc.

The sharp edge 21 cuts through the powder and after the powder is used from the top of the disc, the disc will fit closely against the flange 17 and will be yieldingly 55 held in such position, so that the vanity case can be readily carried in the hand or in a bag without spilling the powder.

The top 11 may be provided with a mirror 60 23 if desired or may be provided in any suitable way with other parts.

For convenience in raising the ring 13 on its hinge, a folded ribbon or the like 24 may be secured to the plate 13 near its edge opposite the hinge 15.

65 Some changes may be made in the con-

struction and arrangement of the parts of my improved vanity case without departing from the real spirit and purpose of my invention, and it is my intention to cover by my claims, any such modifications in structure or use of mechanical equivalents, as may be reasonably included within their scope.

I claim as my invention:

1. In a vanity case, a bottom receptacle, 75 a top hinged thereto, a plate hinged in said receptacle at the side and above the bottom thereof having a central opening, means for holding said plate in position spaced above the bottom of the receptacle, said plate being inclined downwardly and inwardly from its outer edge, a disc supported near one edge on and below the plate for pivotal movement, a spring for normally holding said disc against the lower edge of said plate and closing the opening therein.

2. In a vanity case, a bottom receptacle, 80 a top hinged thereto, a plate hinged in said receptacle at the side and above the bottom thereof having a central opening, means for holding said plate in position spaced above the bottom of the receptacle, said plate being inclined downwardly and inwardly from its outer edge and having a 85 downwardly inclined flange at its inner edge, a disc supported near one edge on and below the plate for pivotal movement, a spring for normally holding said disc against the lower edge of said plate and closing the opening therein.

3. In a vanity case, a bottom receptacle, 90 a top hinged thereto, a plate member hinged in said receptacle above the bottom thereof inclined from the wall of said receptacle 95 downwardly and inwardly, having a central opening, means for normally holding said plate against movement on its hinge, a disc below said opening and a spring for normally holding said disc against the lower edge of said plate and closing the opening therein.

4. In a vanity case, a bottom receptacle, 100 a top hinged thereto, a plate member in said receptacle above the bottom thereof inclined from the wall of said receptacle 105 downwardly and inwardly, and having a central opening, a disc supported on said plate below said opening for pivotal movement and a spring for normally holding said disc against the lower edge of said plate and closing the opening therein, and means for preventing lateral movement of said disc.

5. In a vanity case, a bottom receptacle, 115 a top hinged thereto, a movable plate member in said receptacle above the bottom thereof inclined from the wall of said receptacle 120 downwardly and inwardly, and having a central opening, means for normally holding said plate in position, a disc below said opening supported on the plate 125 130

for movement for opening and closing the opening and for bodily movement with the plate, and a spring for normally holding said disc against the lower edge of said plate and closing the opening therein, and means for preventing lateral movement of said disc and permitting swinging movement thereof toward and from said opening.

10 6. In a vanity case, a bottom receptacle, a top hinged thereto, a plate member hinged

in said receptacle above the bottom thereof inclined from the wall of said receptacle downwardly and inwardly, and having a central opening, a disc below said opening and a spring supported on the disc for normally holding said disc against the lower edge of said plate and closing the opening therein. 15

Des Moines, Iowa, March 10, 1924.

GEORGE E. DAVIS.
